CLAIM

I claim the ornamental design for a stylus, as shown and described.

DESCRIPTION

FIG. 1 are left-side and right-side views of a stylus embodying the new design;

FIG. 2 is a top plan view of the stylus;

FIG. 3 is a bottom plan view of the stylus;

FIG. 4 is a front view of the stylus;

FIG. 5 is a rear view of the stylus; and,

FIG. 6 is a perspective view of the stylus.
